(57) **CLAIM**

The ornamental design for a stool with square support, as shown and described.

DESCRIPTION

FIG. 1 is an underside perspective view of a stool with square support depicting the new design, viewed from the front-left corner;

FIG. 2 is a top perspective view of the stool with square support depicted in FIG. 1, viewed from the rear-right corner; FIG. 3 is a bottom plan view of the stool with square support depicted in FIG. 1;

FIG. 4 is a top plan view of the stool with square support depicted in FIG. 1;

FIG. 5 is a front elevational view of the stool with square support depicted in FIG. 1;

FIG. 6 is a rear elevational view of the stool with square support depicted in FIG. 1;

FIG. 7 is a right side elevational view of the stool with square support depicted in FIG. 1; and,

FIG. 8 is a left side elevational view of the stool with square support depicted in FIG. 1.

The broken lines showing in the drawings are for illustrative purposes only and form no part of the claimed design.
